UNITED STATES PATENT OFFICE.

ALONZO ALDRICH, OF BELOIT, WISCONSIN.

PAPER-MAKING MACHINE.

Application filed November 4, 1921. Serial No. 512,811.

To all whom it may concern:

Be it known that I, ALONZO ALDRICH, a citizen of the United States, residing at Beloit, in the county of Rock and State of Wisconsin, have invented a certain new and useful Improvement in Paper-Making Machines, of which the following is a full, clear, concise, and exact description, reference being had to the accompanying drawings, forming a part of this specification.

My invention relates to machines for making paper.

The principal objects of the invention are to provide a simple and practical machine for making paper, and to produce a machine very much smaller and less complicated than present day paper making machines.

Another object of the invention is to secure efficiency, economy and greater speed in operation.

In the accompanying drawings Fig. 1 is a side elevation of a paper making machine embodying my present invention;

Fig. 2 is a plan view of the same;

Fig. 3 is a view partly in end elevation and partly in cross section; and

Fig. 4 is a cross section taken on line 4—4 in Fig. 3.

In the drawings I show a machine having a base or body 1, in which is mounted a rotary member 2 in the form of a hollow cylinder. The ends of the member 2 are supported in bearings 3—3 supported on pedestals or uprights 4—4 at the ends of the base member 1. The rotary member 2 is to serve as a paper making element and to such end is made of a perforate construction, as for example, by providing it with a plurality of apertures 5—5 terminating in a series of circumferential grooves 6—6. A series of longitudinally extending rods 7 are laid upon the periphery of the cylinder 2, being preferably set in longitudinally extending grooves of about half the depth of the rods 7 so that said rods 7 will project above the periphery of the cylinder 2 only about half their thickness as shown in Fig. 3. A winding wire 8 is wrapped spirally around the cylinder 2 outside of the longitudinally extending rods 7. Two layers of wire cloth 8^a and 8^b are arranged outside of the winding wire 8, the inner or foundation layer 8^a being coarser than the outer layer 8^b.

As a means for rotating the cylinder 2 I show a gear 9 on one end of the same, 55 said gear 9 meshing with a pinion 10 on a rotary drive shaft 11 carrying a driving pulley 12.

A wooden tank 13 is arranged below the cylinder 2 (Fig. 3), said tank having a 60 chamber 13^a for the paper pulp from which the paper is to be made. Within the tank 13 is a horizontal partition 14 through which apertures 15 are formed and vanes or partitions 16—16 extend upwardly from the 65 partition 14 to close proximity to the under side of the rotary cylinder 2. The apertures 15 and vanes 16 are preferably at an inclination to the vertical, as shown in Fig. 3, so as to give the paper pulp a sidewise 70 movement and thereby cross the fibers in the finished paper.

The pulp chamber or vat 13 is supplied with paper pulp from a tank or head box 17 and the connection 18 extending from the tank 17 to the base member 1 and having a channel or duct 19 for the flow of pulp material. Circulation of the paper pulp is secured by a pump 30 connected with a small supplemental tank 31 and also connected 80 with a pipe 32 running back to the main tank or head box 17 and discharging into the same, the discharge being controlled by a valve 33. The supplemental tank 31 has a gate valve 34 controlling the passage or 85 duct between said tank 31 and the pulp chamber 13, the gate valve 34 being adjustable by means of an adjusting screw 35 and wheel 36.

Vacuum boxes 20 and 21 are arranged inside of the cylinder 2 and preferably on the upwardly moving side of the same, as shown in Fig. 1. These boxes 20 and 21 are suspended by suitable means, as for example brackets 22, so that the under sides or walls 95 of the boxes are in contact with the inner surface of the cylinder 2. The brackets 22 are in turn supported by arms 23 secured by bolts 24 to the uprights 4. Adjusting screws 25 adjust the positions of the boxes 20 and 21 and said screws 25 hold the brackets 22 in adjusted positions. The boxes 20 and 21 are connected with pipes 28 by means of branch pipes 29, the pipes 28 running to a suitable blower or other apparatus for producing a vacuum or partial vacuum so that 100 105

air is exhausted from the interior of the boxes 20 and 21 and suction produced therein. The first box 20 draws water from the pulp and the pulp against the wire, and so 5 forms the sheet on the wire. The other box 21 draws water through the wire from the sheet to dry the same. Wear plates 13^b are bolted to the ends of the tank 13 to keep the paper pulp from leaking out at the ends of 10 the tank under the cylinder. When these wear down, they may be removed and others put in their places.

A couch roll 38 is arranged above the cylinder 2, said roll 38 being carried by suitable means, as for example, swinging arms 39-39 pivoted at 40. The roll 38 is made adjustable in a substantially horizontal manner relatively to the arms 39 by means of bolts 41 arranged to move in apertures 42 20 in the arms 39. This adjustment of the roll is controlled by a screw 43 having an end wheel 44 and engaging the movable bearings 45 in which the shaft or axle 46 of the wheel 38 is mounted.

25 A belt or band 47 of felt or other suitable material passes around the roll 38 and also over the top of the paper wheel or cylinder 2. This belt or band 47 also passes between pressing or squeeze rolls 49 and 50 adapted 30 for squeezing moisture out of paper on said belt 47. The roll 38 is supported by swinging arms 51 pivoted at 52 and carrying an adjusting weight 53 and the lower roll 52 being mounted in bearings 54 supported on 35 the lower portion of the frame 55. The bottom roll 50 is provided with a clutch 56 (Fig. 2) and also with the driving pulley 57. The frame 55 is supported on another frame 58 which has arms 59 supporting a roll 60 over which latter the belt or band 47 passes. Another roll 61 is mounted on small pedestals 62 near the base of the frame 58. The belt or band 47 passes first around 40 the roll 61, thence up and over the roll 60, then underneath and around the roll 38 and then between the upper and lower squeeze rolls 49 and 50. The paper which is formed on the wire on cylinder 2 passes from said cylinder 2 on to the felt band 47 passing 45 around the roll 38. The paper travels with the belt 47 from the roll 38 to and between the squeeze rolls 49 and 50, by which latter the remaining moisture is squeezed out.

50 As an arrangement for facilitating the separation of the paper from the wire, on the roll 2, I show a vacuum box 63 on the top of the roll 2, said box 63 being connected by a pipe 64 with some suitable vacuum producing apparatus to create a condition of 55 suction in the box 63.

60 It will be seen that the machine is more simple and compact and is a great deal smaller and less complicated than present day paper machines, and it can be run a 65 great deal faster.

It will be understood that changes and modifications may be made without departing from the spirit of the invention.

What I claim is:

1. A paper machine comprising a rotary forming member, a vat or tank for the pulp for said forming member and suction means tending to strip the paper film from the rotary forming member, said suction means comprising a suction box arranged in position on the outer side of the rotary forming member and close to the same so as to exert suction force on the paper strip before it actually leaves the forming member. 70

2. A paper machine comprising a tank or vat, a rotary member for making paper, said member being mounted to permit its lower portion to be submerged in the pulp in said tank or vat, and the remainder to be unsubmerged, means for forming the paper sheet on the submerged portion of said member, means for withdrawing moisture from the sheet on said member, a roll cooperating with said rotary member to receive the paper sheet from the same, and means tending to remove the paper from said rotary member before it reaches said roll and facilitate its movement on to said roll. 80

3. The combination with a tank or vat and a rotary forming member arranged above the tank or vat with its lower portion immersed in the material in the vat, of a suction box on the inner side of the rotary forming member about the level of the material in the tank or vat for forming the film on the rotary member and a second suction box also located within the forming member and above the first mentioned box for withdrawing moisture from the film. 90

4. The combination with a tank or vat and a rotary forming member arranged above the tank or vat with its lower portion immersed in the material in the vat, of a suction box on the inner side of the rotary forming member about the level of the material in the tank or vat for forming the film on the rotary member and a second suction box also located within the forming member and above the first mentioned box for withdrawing moisture from the film, and a third suction box on the outer side of the rotary member for stripping the film from the same. 100

5. The combination of a tank or vat for the paper pulp, a rotary member mounted above said vat and arranged so that its lower portion only shall be constantly immersed in the pulp in said vat, a tank at one side of the vat having a duct or passage by which the pulp may pass from said tank to the vat and means for inducing a flow of the pulp from the tank to the vat, said means comprising a circulatory system involving a pump and return flow pipe extending from the tank to the vat. 110

6. The combination of a tank or vat for the paper pulp, a rotary member mounted above said vat and arranged so that its lower portion only shall be constantly immersed in the pulp in said vat, a tank at one side of the vat having a duct or passage by which the pulp may pass from said tank to the vat and means for inducing a flow of the pulp from the tank to the vat, said means com-

prising a circulatory system involving a ¹⁰ pump and return flow pipe extending from the tank to the vat, said tank having a valve controlling the circulation in said system.

In witness whereof, I hereunto subscribe my name this 27th day of October, A. D., 1921.

ALONZO ALDRICH.
